ORAL EVACUATOR POWER UNIT

Luis Beguristain, St. Paul, Minn., assignor to The Torit Corporation, St. Paul, Minn., a corporation of Minnesota

Filed Apr. 21, 1969, Ser. No. 16,834

Term of patent 14 years

Int. Cl. D24—03

U.S. Cl. D24—1

FIG. 1

FIG. 2

FIG. 3

FIG. 4

FIG. 5

FIG. 6

FIG. 1 is a perspective view of an oral evacuator power unit showing my new design;

FIG. 2 is a front elevation view of the same;

FIG. 3 is a right elevation view of the same, the left elevation view being a mirror image;

FIG. 4 is a rear elevation view of the same;

FIG. 5 is a top plan view of the same; and

FIG. 6 is a bottom plan view of the same.

I claim:

The ornamental design of the oral evacuator power unit, as shown and described.
